UNITED STATES PATENT OFFICE.

JOB TATTON, OF NORTH BAY, ONTARIO, CANADA.

JACK.

1,391,594.

Specification of Letters Patent. Patented Sept. 20, 1921.

Application filed December 16, 1920. Serial No. 431,280.

To all whom it may concern:

Be it known that I, JOB TATTON, a subject of the King of Great Britain, residing at North Bay, Province of Ontario, Canada, have invented certain new and useful Improvements in Jacks; and I do hereby declare that the following is a full, clear, and exact description of the invention, such as will enable others skilled in the art to which it appertains to make and use the same.

The present invention relates to new and useful improvements in jacks.

The primary object of the invention is the provision of a jack so constructed that the same will have considerably greater lifting power than the jacks now in ordinary use.

Another object of the invention is the provision of a jack so constructed as to provide for a double lifting power, that is, a direct upward pressure from the actuating lever to the raising mechanism and also an indirect power through cam mechanism operatively connected thereto.

Still another object of the invention is the provision of a jack such as above described in which the parts thereof are so formed as to render the said jack durable and less liable to get out of order than the jacks now in use.

A further object of the invention is the provision of a jack such as above referred to including novel means for manipulating the pawls so that they will act to raise or to lower the jack as desired.

A still further object of the invention is the provision of a jack such as above referred to, which will be comparatively simple and inexpensive to manufacture, reliable and efficient in use, and readily operated.

With the above and other objects in view, the present invention resides in the novel features of construction, formations, combinations and arrangements of parts to be hereinafter more fully described, claimed, and illustrated in the accompanying drawings forming a part of the present application, and in which:

Figure 1 is a side elevation of a jack constructed in accordance with the present invention;

Fig. 2 is a side view of a body portion

of the jack showing the pawls positioned for lowering the same;

Fig. 3 is a similar view showing the pawls arranged for raising the same;

Fig. 4 is a vertical sectional view taken through that portion of the invention shown in Fig. 3 with the operating lever in raised position;

Fig. 5 is a similar view showing the lever in lowered position;

Fig. 6 is a horizontal sectional view taken through the body portion of the jack;

Fig. 7 is a similar view taken through the pawl actuating means;

Fig. 8 is a detail side view of the pawl actuating means and plate which supports the same;

Fig. 9 is a detail perspective view of the connecting link;

Fig. 10 is a similar view of the upper pawl; and,

Fig. 11 is a similar view of the lower pawl.

Referring now to the accompanying drawings by corresponding characters of reference throughout the several views, the numeral 15 designates in general my improved jack, which comprises a base 16, from which extends a vertical standard 17 which is securely braced by the ribs 18 to the longer of which are connected the usual handle members 19.

An enlarged body portion 20 is formed at the upper end of the standard 17 and is provided with a vertical passage 21 which communicates with a corresponding passage 22 formed in the standard 17.

In these passages 21 and 22 is vertically mounted a lifting bar 23 which is provided at its inner edge with a series of rack teeth 24 for a purpose to be later explained. The bar 23 has secured to its upper end the usual head 25.

A recess 26 is provided in the body portion 20 and opens through one side of the body portion as shown at 27.

A supporting plate 28 closes the intermediate portion of the opening 27, while upper and lower plates 29 and 30 close the remainder of the opening 27. These plates are firmly retained in position against displacement by the screw elements 31.

The recess 26 is provided at its upper side with a vertical extension 32 in which is slidably mounted a lifting block 33. This block 33 is normally forced to its lowermost position by a spring 34 which is seated in the recess 35 formed in the upper end of the block 33 and engages the upper end of the extension 32.

The outer edge of the block 33 is cut away, 10 as shown at 36 and provided with a substantially circular recess 37 in which is pivotally engaged the rounded end 38 of a pawl 39 which is designed to engage the teeth 24 above referred to and upon the upward 15 movement of the block 33 raise the bar 23, one tooth at a time.

The outer edge of the block 33 is provided with a second circular recess 39, and adjacent one edge thereof a rounded extension 20 40. The recess 39 is adapted to receive the rounded nose 41 of the head 42 of an operating lever 43, while the rounded extension 40 of the block 33 is adapted to fit within the rounded recess 44 formed in the end of the 25 head 42 adjacent the nose 41 thereof.

Obviously, as the lever 43 is forced downwardly in the direction of the arrow in Fig. 4, the said head 42 will engage the block 33 forcing the same upwardly as shown in the 30 position in Fig. 5.

A cam member 45 is pivoted as at 46 within the recess 26 and is provided with an outwardly extending cam portion 47 adapted to be engaged by the lower side of the 35 head 42.

The forward or inner end of the cam member 45 is provided with a recess 48 in which is inserted one end of the link 49 the opposite end of which fits within a recess 50 provided in the lower end of the lifting block 33. Obviously when the lever 43 is forced 40 downwardly in addition to the head 42 by its engagement with the block 33 forcing the said block upwardly, the cam portion 47 of the member 45 will be forced downwardly, which forces the inner end thereof upwardly and through the medium of the link 49 likewise forces the block 33 upwardly, thus increasing the lifting power of the jack.

50 A pawl 51 is pivotally mounted, as shown at 52, in a recess 53 in the lower end of the body portion 20, and engages the teeth 24 of the bar 23 to prevent said bar from slipping when the pawl 39 is disengaged from the 55 teeth.

The pawl 51 is provided with a depending extension 54 from which projects a pin 55, while a corresponding pin 56 extends from the before described pawl 39.

60 A shaft 57 is rotatably mounted in the plate 28, and is provided at its inner end with a block 58 between which and the clamps 59 are held the oppositely extending spring pawl actuating elements 60 and 61.

65 These elements have the terminals thereof

bent upon themselves as at 62 and 63 to engage respectively the pins 56 and 55.

An arm 64 extends laterally from the shaft 57 being held rigid thereon, as shown at 65.

A spring actuated pawl 66 is disposed in the free end of the arm 64, and is designed to engage either the upper or lower notches 67 or 68 formed in the rack 69 secured to the inner edge of the opening 27. The plate 28 70 is held in position against displacement by the fastening element 70 clearly shown in Figs. 1, 2 and 3.

Obviously when the shaft 57 is rotated so that the pawl 66 engages the notch 67, the 80 pawls 39 and 51 will be held in such position that the movement of the lever 43 raises the bar 23, but when the shaft is turned so that the pawl 66 engages the notch 68, the pawls will actuate through the instrumentality of the spring members 60 and 61 to lower the said bar 23.

As shown in the drawings, the shaft 57 may be concealed by a suitable cap 71 which may be inserted thereover for preventing injury to the jack in case the same falls over and strikes on the end of the shaft 57.

90 From the foregoing description, taken in connection with the accompanying drawings, it will be manifest that a jack is provided which will fulfil all of the necessary requirements of such a device, and it should be understood in this connection, that various minor changes in the specific details of construction can be resorted to within the 95 scope of the appended claims, without departing from the spirit or sacrificing any of the advantages of the invention.

Having thus fully described the invention, what I claim as new and desire to protect 100 by Letters Patent is:—

1. The combination in a jack, of a body portion, a lifting bar mounted therein, a lever operatively connected to said lifting bar for raising the latter, and additional 110 means actuated by the lever for raising said lifting bar.

2. The combination in a jack such as described, of a body portion, a lifting bar slidably mounted therein, a lever operatively connected to the lifting bar, and a cam mechanism operated by the lever for exerting upward pressure upon the lifting bar upon the actuation of the lever.

3. A jack such as described comprising a 120 body portion, a lifting bar slidably mounted therein, a lifting block mounted in the body portion, an operative connection between the lifting block and the lifting bar, a lever for actuating the lifting block, and additional 125 means actuated by the lever and engaging the lifting block for exerting an upward pressure thereon.

4. The combination in a device of the character described, of a body portion, a 130

lifting bar slidably mounted therein, a lifting block mounted in said body portion and operatively connected to the lifting bar, a lever mounted in the body portion for engagement with the lifting block for actuating the latter, and a cam mechanism connected to the lifting block and actuated by the lever, substantially as and for the purposes set forth.

5 10 5. A jack such as described, comprising a body portion, a lifting bar slidably mounted therein, a head upon said lifting bar, rack teeth provided upon said lifting bar, a lifting block mounted in the body portion, a pawl carried thereby for engagement with the rack teeth of the lifting bar, a lever mounted in the body portion and having operative engagement with the lifting block for actuating the latter, additional means 15 20 connected with the lifting block and the lever, and a second pawl mounted in the body portion of the jack and engaging the rack teeth.

6. In a jack such as described, the combination of a body portion, a lifting bar slidably mounted therein, a lifting block slidably mounted in the body portion, a pawl carried thereby, teeth provided upon the lifting bar for engagement with the pawl, a cam member pivoted in the body portion, a link connecting the cam member and the lifting block, an operating lever pivoted in the body portion and engaging the pivoted cam member and operatively connected to 30 35 the lifting block, and a second pawl pivoted in the body portion and engaging the teeth of the lifting bar.

7. The combination in a jack such as described, of a body portion, a lifting bar having teeth thereon slidably mounted in said body portion, a lifting block mounted in the body portion, a spring for forcing the latter to its lowermost position, a lever pivotally connected to the lifting block for raising 40 45 the latter, a pawl carried by the lifting block and engaging the teeth of the lifting bar, a second pawl mounted in the body portion and engaging the teeth of the lifting bar, a cam member pivotally mounted in the body portion in the path of the lever for actuation thereby, and a link connecting the cam member and the lifting block.

50 8. The combination in a jack such as de-

scribed, of a body portion, a lifting bar having teeth slidably mounted in the body portion, a lifting block mounted in the body portion, a lever for actuating said block, a cam member actuated by the lever and operatively connected to said block, a pawl carried by the block for engagement with the teeth of the lifting bar, a second pawl mounted in the body portion and engaging the teeth of the lifting bar, and spring members engaging said pawl, as and for the purposes set forth.

9. The combination in a jack such as described, of a body portion, a lifting bar having teeth therein slidably mounted in the body portion, a lifting block mounted in the body portion, a pawl carried thereby for engagement with the teeth of the lifting bar, a lever for actuating the lifting block, a cam member for actuating the lifting block and operated by the lever, a second pawl engaging the teeth of the lifting bar, spring members engaging said pawls, and means for changing the position of said spring members and said pawls, substantially as and for the purposes set forth.

10. The combination in a jack such as described of a base, a shank extending therefrom, a body portion carried by the shank, a lifting bar having teeth at one edge thereof slidably mounted in the body portion of the shank, a head upon said lifting bar, a lifting block slidably mounted in the body portion, a spring for normally forcing said block to its lowermost position, a pawl carried by the block and engaging the teeth of the lifting bar, a lever operatively connected to the lifting bar for actuating the same, a cam member pivoted within the body portion and actuated by the lever, a link connecting the cam member and lifting block, a second pawl pivoted in the body portion and engaging the teeth of the lifting bar, pins extending from said pawls, a rotatable block, springs carried thereby and engaging the pins projecting from the pawls, means for rotating the block, and means for locking the block in adjusted positions, substantially as and for the purposes set forth.

In witness whereof I have hereunto set my hand.

JOB TATTON.
